UNITED STATES PATENT OFFICE.

FOWLER RICHARDSON, OF LEBANON JUNCTION, KENTUCKY, ASSIGNOR OF ONE-HALF
TO LORENZO D. GREGORY AND CYRUS E. MORGAN, BOTH OF ELIZABETHTOWN,
KENTUCKY.

LIFTING JACK.

Application filed January 13, 1926. Serial No. 81,053.

This invention relates to improvements in lifting jacks, having for an object to provide a lifting jack so constructed as to render the same especially advantageous for use in replacing worn bearings in the journal boxes of railway cars, whereby the box may be elevated independently of the car wheel and its axle in order that ready access may be had to the worn bearing to effect its removal, and likewise, that a new bearing may be conveniently and properly placed therein.

Another and equally important object of the invention is to provide the jack with a novel form of anchoring leg adapted to have adjustable bearing upon an adjacent portion of a car wheel whereby a downward pressure will be directed to that wheel in order that the same will be retained upon its rail during the raising of the journal box for replacement of the bearing.

Other objects of the invention will be in part obvious and in part pointed out hereinafter.

In order that the invention and its mode of operation may be readily understood by persons skilled in the art, I have in the accompanying illustrative drawings, and in the detailed following description based thereupon set out one possible embodiment of the same.

In these drawings:—

Figure 1 is a side elevation of the improved jack having a portion of the anchoring means broken away and shown in section and also, the anchoring leg engaged with the inner peripheral surface of a car wheel, and

Figure 2 is a side elevation of the improved jack having portion broken away.

Having more particular reference to the drawings, in connection with which like characters of reference will indicate corresponding parts throughout, it is to be understood that my invention resides primarily in the provision of an attachment for railway jacks whereby said jacks will serve to direct a downward pressure or stress upon an adjacent portion of a car wheel whereby to retain said wheel upon its track during the raising of the journal box thereof for the replacement of bearings in the same. To this end, the invention therefore comprises certain novel means which may

be attached to various or different forms or designs of railway jacks now prevalent in the art.

For purposes of illustration, I have shown my invention as being applied to a form of railway jack identified herein in its entirety by the numeral 1, said jack comprising a body or casing portion carried upon a suitable base 2 while a screw threaded rod or shaft 3 extends from the upper end of this body portion or casing and carries the usual saddle or head 4 thereupon adapted to be engaged under the object to be elevated or "jacked". Suitable operating means are connected or connectible with the screw threaded rod or shaft 3 whereby to effect the raising and lowering of the same together with the saddle or head 4.

The invention may be stated to comprise an outwardly curved anchoring leg 5 having an attaching bracket 6 pivoted to the inner end thereof as is indicated at 7 while the outer or free end of said leg 5 is provided with an outwardly curved or laterally offset foot 8 carrying upon its upper side and adjacent its point of jointure with the leg 5, relatively spaced apertured ears 9 for a purpose which will be presently described.

When pivotally connected to the lower portion of one side of the casing or body portion of the jack 1 as is shown in the Figure 1, the curved anchoring leg 5 is adapted to be swung toward and away from said body portion of the jack so that, at times, the outwardly curved or laterally offset foot 8 will be brought into engagement with a portion of the inner peripheral surface of a car wheel 10 resting upon the usual railway track 11, such car wheel having its axle received in the usual journal box 12 in which bearings are arranged and retained.

In the replacing of worn bearings in journal boxes such as indicated herein by the numeral 12, it is the practice to effect such replacement while the railway cars are upon their tracks, such as indicated at 11 and 100 therefore, the prevalent practice is to first connect or anchor the car wheel 10 to its particular track 11 by a clamp or similar connection whereupon a jack is placed upon an adjacent rail tie or other surface and is operated so that the saddle 4 thereof will be moved upwardly into engagement with and will elevate the journal box 12 to a point

whereat the worn bearings may be conveniently removed and replaced by new ones. Such practice, however, involves additional and excessive labor upon part of workmen 5 engaged in the operation and likewise, is absorbing of considerable time. Therefore, with a view toward providing the anchoring leg 5 of my invention with means for maintaining the same in an engaged position with 10 one portion of the inner peripheral surface of the car wheel 10 and also, for directing a downward stress to said leg 5 and foot 8 which will be sufficient to retain the car wheel 10 upon its track 11, I provide the device 15 with longitudinally aligned screw threaded rods 13 and 14, engaging upon the upper end of the rod 13 and attaching plate 15 adapted to be fixedly secured to the aforesaid side of the body portion or casing adjacent the upper end thereof as is shown in 20 the Figure 1; apertured bearing ears 16 being formed upon the plate whereby to permit of pivotal connection of said end of the rod 13 thereto as indicated by the numeral 25 17. The opposite or outer end of the rod 14 is also provided with an apertured extremity adapted to be received between the apertured ears 9 formed upon the upper side of the foot 8 whereupon a pivot pin 17 30 is passed therethrough, hence, effecting pivotal connection as between the leg and foot and the rod 14. A turnbuckle 18 is engaged with the adjacent screw threaded portions of the several rods 13 and 14. It is obvious 35 that with turning of the turnbuckle 18, the screw threaded rods 13 and 14 may be drawn together or forced apart with respect to each other, hence, imparting during such operation, pivotal movement to the foot carrying leg 5.

In usage of the improved jack equipped with the invention, the jack is placed in position as is shown in the Figure 1, directly beneath the journal box 12 which is to be raised and to have bearings replaced therein. The leg 5 with its outwardly curved foot 8 is positioned so as to be arranged in proximity to the car wheel 10 and with this positioning, the turnbuckle 18 is rotated in 45 a direction to cause relative outward movement upon part of the several rods 13 and 14, hence, moving the foot 8 of the anchoring leg 5 downwardly into engagement with a portion of the inner peripheral 50 surface of the car wheel 10 as is shown in the Figure 1. The said foot 8 is engaged with the inner peripheral surface of the car wheel 10 under a pressure sufficient to absolutely insure the retention of 55 said car wheel upon its rail 11 irrespective of the direction of upward stresses or lifting movement to the journal box 12. Subsequently to proper anchoring of the car wheel 10 upon its rail 11, the rod 3 is elevated so as to bring the saddle 4 thereof into 60 engagement with the journal box 12 whereupon said journal box will be raised to a point whereat convenient access may be had to the worn bearings therein, following which such bearings may be readily removed 65 and replaced by others. During elevation of the journal box 12, that is, in the process of replacement of the worn bearings therein, it will be understood that the car wheel 10 will be prevented from having any vertical motion or movement whatsoever with respect to the rail 11, since, as aforesaid, the leg 5 with its outwardly curved foot 8 is engaged with said car wheel under a pressure sufficient to absolutely insure retention of this 70 latter upon its rail. Likewise, it will be appreciated that the positive engagement as effective between the foot carrying leg 5 and the car wheel 10 will be such as to positively locate the jack body portion or casing against undesirable shifting movement during that period of its initial engagement with the under side of the journal box 12. Thus, it will follow that an effectual raising 75 of the journal box 12 upon the shaft 3 and saddle 4 of the jack will result.

When replacement of the bearings in the box 12 has been effected, the shaft 3 is operated in a manner to return the same to its normal or lowermost position with respect to the journal box 12 hence, permitting the bearings in said box to be re-engaged with the car wheel axle. At this time, the turnbuckle 18 is rotated in a reverse direction from that hereinbefore described, causing the screw threaded rods 13 and 14 to be moved in a direction toward each other and by consequence, removing the outwardly curved foot 8 of the leg 5 from the previously engaged inner peripheral portion of 80 the car wheel 10.

By reason of the fact that this anchoring attachment is connected to a jack through the medium of the attaching plates 6 and 15, it will be understood that such device 85 may be successfully used in connection with various forms or types of jacks now generally in use for this particular purpose, without in any way effecting material modification thereof.

Manifestly, the construction shown is capable of considerable modification, and such modification as is within the scope of my claim, I consider within the spirit of my invention.

I claim:—

In combination with a jack of the character described, an anchoring leg curved upon itself throughout its length and having an acutely curved and outwardly disposed foot formed integral with the outer end thereof, the free extremity of said foot being rounded and being so disposed as to directly engage with an adjacent portion of the inner peripheral surface of a car wheel,

relatively spaced upstanding apertured ears formed integral with the upper side of said foot, an attaching plate pivotally connected to the remaining end of the anchoring leg and detachably connected to one side and lower portion of the jack body, a pair of longitudinally aligned screw threaded rods, a turnbuckle interconnecting said screw threaded rods, the lower end of one of said

rods being pivotally connected between the upstanding apertured ears aforesaid, an attaching plate pivotally connected to the upper end of the remaining rod and detachably connected to said side of the jack body adjacent its upper end.

In witness whereof I have hereunto set my hand.

FOWLER RICHARDSON.
